(57) **CLAIM**

The ornamental design for an ear plug for swimmers, as shown and described.

DESCRIPTION

1.1 is a front elevation view of an ear plug for swimmers showing our new design;

1.2 is a left side elevation view thereof;

1.3 is a right side elevation view thereof;

1.4 is a top plan view thereof;

1.5 is a bottom plan view thereof;

1.6 is a rear elevation view thereof; and

1.7 is a rear perspective view thereof.

The broken lines in the drawings illustrate portions of the ear plug for swimmers that form no part of the claimed design.
